UNITED STATES PATENT OFFICE.

LOUIS MYERS, OF NEW YORK, N. Y.

PENCIL-SHARPENING MACHINE.

1,043,861.

Specification of Letters Patent. Patented Nov. 12, 1912.

Application filed August 16, 1911. Serial No. 644,367.

To all whom it may concern:

Be it known that I, LOUIS MYERS, a citizen of the United States, residing in the borough of Manhattan, city, county, and State of New York, have invented certain new and useful Improvements in Pencil-Sharpening Machines, of which the following is a clear, full, and exact description.

The present invention relates to improvements in machines for sharpening pencils and the object of the invention is to improve and simplify the construction and operation of such machines.

In the improved machine, I employ a pencil holding and feeding device which is adapted to grasp a pencil and automatically feed it by gravity toward the sharpening cutter which is preferably operated by hand. This clamp for holding the pencil is mounted to slide vertically in the machine frame, and suitable latching means are provided for supporting the clamp in elevated position while the pencil is being inserted. The latching means are automatically operated for releasing the clamp at the start of the sharpening operation. A suitable automatically operated gage is provided for limiting the insertion of the pencil in the clamp, and an adjustable gage is provided for determining the extent of the sharpening operation.

In order that my invention may be fully understood, I will first describe the same with reference to the accompanying drawings and afterward point out the novelty more particularly in the annexed claims.

In said drawings: Figure 1 is a vertical sectional view of my improved pencil sharpening machine. Fig. 2 is a plan view of the same. Fig. 3 is a transverse sectional view taken on the section line 3-3 of Fig. 1 looking in the direction indicated by the arrow. Fig. 4 is a transverse section on line 4-4 of Fig. 1. Fig. 5 is a transverse section just above the top portion of the machine showing the latching levers and their gaging device. Fig. 6 is a vertical section on line 6-6, Fig. 5. Fig. 7 is a section on line 7-7, Fig. 5. Fig. 8 is a longitudinal sectional view, partly in plan, of the pencil holding and feeding clamp, and gage to determine amount of feeding movement. Fig. 9 is a detail view of said gage, and Fig. 10

is a sectional detail view on the line 10-10 of Fig. 2, showing more particularly the construction of the gage and stop device.

1 is the casing of the improved machine which in the form illustrated in the drawings, is of approximately cylindrical shape with a slight enlargement at the base to receive a horizontally movable drawer 2 into which the pencil shavings fall in the operation of sharpening a pencil.

The casing 1 is provided with a removable top plate 5 from which depend the two tubular guides or supports 6 and 7 which are connected at their lower ends, within the casing 1, by a cross bar or brace 8. The top plate 5 is secured to the casing by any suitable means (not shown) and supports all of the operative parts of the machine.

An adjustable bearing screw 10 is threaded through the cross bar 8 and has journaled upon it the lower end of a rotary casting 12 which constitutes a guide for the sharpened end of the pencil and a carrier for the sharpening cutter. The member 12 is formed at its upper end with a bearing which receives a circular flange or journal 12^a on the top plate 5. This member 12 is formed with parallel arms 13 and 14 projecting laterally from it in planes inclined to the horizontal, and adjustably mounted in said arms are the cone-pointed bearing screws 15 and 16 upon which is journaled a cylindrical cutter 20 having spiral cutting ribs or blades as in the well known form of milling cutter. The bearings 15 and 16 are set at an angle with relation to the axis upon which the carrier 12 is journaled so as to form with the open sided conical guiding recess 12^b of carrier 12 a contracted throat into which the pointed end of the sharpened pencil projects.

Secured to the upper end of the cutter 20 is a bevel gear 25 which is in constant mesh with the internal ring gear 26 rigidly secured to and supported by the top plate 5 between the tubular supports 6 and 7, by spacing sleeves 22 shown in Fig. 1. Secured to the upper end of the member 12 is a bevel gear 30 meshing with a similar bevel gear 31 keyed to the inner end of a short horizontal shaft 32 which is journaled in the cylindrical bearing 33 secured to the upper face of the top plate 5. This shaft 32 car-

ries at its outer end a crank handle 35. By turning the handle 35 the member 12 is rotated upon its bearings 10 and 12^a, and carries with it the cutter cylinder 20 which, 5 by reason of the engagement of bevel gear 25 with stationary gear 26, will also rotate upon its bearings 15 and 16. The carrier member 12 is formed with a conical recess 12^b in axial alinement with the axis of rotation of the member 12. This recess 12^b is open upon one side to receive the cutting face of the milling cutter 20.

The pencil holding and feeding clamp comprises a horizontal tubular member 40 secured upon the upper ends of the downwardly presented guide rods 42 and 42 which slide in the tubular supports 6 and 7 and the co-operating pencil engaging bolts 43 which slide in the longitudinal bore of member 40. 15 Member 40 has a central vertical pencil-receiving opening 51 in line with the axis of the cutter-carrying member 12. Clamping bolts 43 are arranged upon opposite sides of the opening 51. Each of the bolt 20 members 43 is formed with a V-shaped inner end to effectively engage pencils of various sizes and shapes.

Depending from each bolt 43 is a pin 46 passing freely through a longitudinal slot 46^a in the bottom wall of member 40 and engaging an angular slot 47 in a rotary cam plate 48 formed with an operating finger 49. The cam plate 48 is journaled upon an annular flange 50 surrounding the pencil-receiving opening 51 of member 40. A second finger 53 projects from the clamp member 40 adjacent to the finger 49 to afford convenient means for operating cam plate 48 by grasping the fingers 49 and 53 between 40 the thumb and first finger of the hand. By rotating the plate 48 the two pencil clamping bolts 43 are moved outwardly in their support to separate them for the insertion of a pencil in the clamp.

45 Each of the rods 42 is formed adjacent to its lower end with a transverse slot 60 which is presented just below the top plate 5 when the pencil holding clamp is elevated. Pivoted upon set screws 65 in the top plate 5 50 are the latching levers 66 and 67, each of which is formed with a latching arm 68 presented in position to engage in one of the slots 60 for holding the pencil clamp in raised position. The latching lever 66 is 55 formed with a socket extension 69 engaging the rounded end 70 of the lever 67 to couple the two latching levers so that they will operate in unison. A spring 75 suitably mounted upon the top plate 5 engages the 60 coupled latching levers 66 and 67 to give them a normal tendency to move into latching engagement with the notches 60 of rods 42.

The latching lever 66 is formed with a gage plate 72 which projects horizontally toward the axis of pencil receiving opening

51 of the clamp 40. This plate 72 extends across the pencil receiving opening when the clamp is held in elevated position by the engagement of the latching levers with the notched rods 42 and serves the purpose 70 of gaging the entrance of the pencil in the clamp.

Projecting downwardly from one of the coupled latching levers 66, 67 is a cam block 73. This block 73 is presented in the circular path of the arm 13 of the member 12 above referred to, so that in the operation of the machine, the arm 13 will engage cam 73 and move the coupled latching levers 66 and 67 outwardly to disengage them from the rods 42 to permit the lowering of the clamp by gravity. The same operation withdraws the gaging plate 72 from the path of the pencil. After its release, the clamp continues to move downwardly by gravity 85 as fast as the pencil is cut away by cutter 20. The latching levers are held in disengaged position by their engagement with the plane faces of rods 42.

The degree to which the sharpening operation is carried is dependent upon the extent of movement of the clamp with the pencil toward the sharpening cutter. To determine the extent of this pencil feeding movement of the clamp, I mount in a groove 90 82 upon one face of the clamp 40 an adjustable gage plate 80 held by means of set screw 81 which bears on the bottom wall of the groove and binds the plate against the undercut side walls. This gage plate 80 is 100 formed with an outwardly bent end 83 by which it can be shifted horizontally, and an index or pointer 84 operating upon a scale or series of marks 85 which may be identified by the words "fine," "medium," 105 "coarse" and "crayon" to indicate the different degrees to which pencils may be sharpened. A series of stopping steps 86 are adapted to be struck by the projection 83 on the gage. It will be understood that the adjustment of the gage plate 80 inwardly and outwardly will arrest the downward movement of the pencil feeding clamp sooner or later in the pencil sharpening operation.

110 The operation of sharpening a pencil with my improved machine will be understood from the following brief explanation. The pencil holding clamp is raised by hand or in any suitable manner until the latching levers 66 and 67 engage the notches in the rods 42 for supporting the clamp in elevated position. In this position of the clamp, the pencil limiting gage 72 will be presented across the central opening in the top plate 120 125 5. The operator then opens the clamp by pressure upon the finger 49 and inserts the pencil until its inner end rests upon the gage plate 72, when he releases finger 49 to permit the clamping bolts to securely clamp the 130

pencil. Crank 35 is then rotated to the right, causing arm 13 to operate upon cam 73 for disengaging the latching levers 66 and 67 from rods 42, with the result that the 5 clamp and the pencil will fall by gravity until the inner end of the pencil is arrested by engagement with the contracted throat 12^b and the face of the cutter 20. The rotation of the crank is continued causing the milling cutter 20 to rapidly shave off the end of the pencil as long as it advances by the action of the clamp. The operation is continued until the movement of the clamp is arrested by the engagement of projection 83 10 on the limiting gage 80 with one or the other of stops 86, when it will be found that the pencil is sharpened to the degree desired. The pencil can then be removed by opening the clamp by again pressing upon the finger 20 15 49.

I have shown and described a sharpening cutter operated by a planetary system of gears, but I would have it understood that other forms of rotary sharpening cutters 25 may be used in my machine without departing from the spirit of my invention.

The arrangement and construction of the operative parts of my improved pencil sharpening machine in upright position is 30 important, first, because of the natural discharge of the shavings from the pencil by gravity into the receptacle at the bottom of the casing, thereby effectively freeing the working parts of the machine from the dust 35 and shavings; second, because of the simplicity and effectiveness of the gravity-operated vertically moving pencil holding clamp in conjunction with the sharpening cutter which rotates in a horizontal plane; 40 and third, because of the simplicity of the machine from a manufacturing standpoint. All of the parts are carried by the top plate 45 which can readily be removed for the adjustment and repair of the parts. The gravity clamp can be removed separately by simply withdrawing the guide rods 42 from the tubular guides 6 and 7, the latching device being first disengaged from the notches of the guide rods.

50 What I claim is:

1. In a pencil sharpening machine, the combination of a sharpening cutter which cuts in fixed position relatively to the pencil-receiving socket and constitutes a rest for 55 the lower end of a pencil, and means for operating the said cutter, with a gravity-operated pencil-holding clamp movable toward and away from said cutter and supported by said cutter and the pencil, and 60 means forming a part of the machine for supporting said clamp and guiding it independently of the pencil.

2. In a pencil sharpening machine, the combination of a sharpening cutter and 65 means for operating it, with a pencil-hold-

ing clamp movable toward and away from said cutter, and a gage between the cutter and clamp for limiting the entrance of the pencil in said pencil-holding clamp.

3. In a pencil sharpening machine, the 70 combination of a sharpening cutter and means for operating it, with a pencil-holding clamp movable toward and away from said cutter, an adjustable gage adapted to limit the movement of the clamp toward the 75 cutter, and a gage separately positioned for limiting the entrance of the pencil in said pencil-holding clamp.

4. In a pencil sharpening machine, the 80 combination of a sharpening cutter and means for operating it, with a gravity operated pencil holding clamp movable toward and away from said cutter, a latching device for supporting said clamp in raised position, and means actuated by the cutter operating means for releasing said latching device.

5. In a pencil sharpening machine, the 90 combination of a sharpening cutter and means for operating it, with a pencil-holding clamp movable toward and away from said cutter, an automatic latching device for supporting said clamp in outward position, and an adjustable gage adapted to limit the 95 movement of the clamp toward the cutter.

6. In a pencil sharpening machine, the 100 combination of a sharpening cutter and means for operating it, with a pencil-holding clamp movable toward and away from said cutter, an automatic latching device for supporting said clamp in outward position, a gage for limiting the entrance of the pencil in said pencil-holding clamp, and an adjustable gage adapted to limit the movement of the clamp toward the cutter.

7. In a pencil sharpening machine, the 105 combination of a sharpening cutter and means for operating it, with a gravity operated pencil holding clamp movable toward and away from said cutter, means for guiding said clamp away from said cutter, an automatically operating latching device adapted to engage the clamp and support it in raised position, and means actuated by the cutter operating means for releasing said latching 115 device.

8. In a pencil sharpening machine, the 120 combination of a sharpening cutter and means for operating it, with a gravity operated pencil holding clamp movable toward and away from said cutter, means actuated by said cutter operating means apart from the pencil for guiding said clamp away from said cutter, and an automatically operating latching device adapted to engage the clamp 125 and support it in raised position.

9. In a pencil sharpening machine, the 130 combination of a sharpening cutter and means for operating it, with a gravity operated pencil holding clamp movable toward

and away from said cutter, and an adjustable gage limiting the movement of the clamp toward the cutter.

10. In a pencil sharpening machine, the combination of a sharpening cutter and means for operating it, with a gravity operated pencil holding clamp movable toward and away from said cutter, and a gage between the cutter and clamp for limiting the entrance of the pencil in said pencil holding clamp.

11. In a pencil sharpening machine, the combination of a sharpening cutter and means for operating it, with a gravity operated pencil holding clamp movable toward and away from said cutter, an adjustable gage adapted to limit the movement of the clamp toward the cutter, and a gage for limiting the entrance of the pencil in said pencil holding clamp.

12. In a pencil sharpening machine, the combination of a sharpening cutter and means for operating it, with a gravity operated pencil holding clamp movable toward and away from said cutter, an automatic latching device for supporting said clamp in raised position, and an adjustable gage adapted to limit the movement of the clamp toward the cutter.

13. In a pencil sharpening machine, the combination of a sharpening cutter and means for operating it, with a gravity operated pencil holding clamp movable toward and away from said cutter, an automatic latching device for supporting said clamp in raised position, a gage for limiting the entrance of the pencil in said pencil holding clamp, and an adjustable gage adapted to limit the movement of the clamp toward the cutter.

14. In a pencil sharpening machine, the combination of a sharpening cutter and means for operating it, with a gravity operated pencil holding clamp movable toward and away from said cutter, a latching device for supporting said clamp in raised position, and a pencil gage operated by said latching device for limiting the entrance of the pencil in said clamp.

15. In a pencil sharpening machine, the combination of a sharpening cutter and means for operating it, with a gravity operated pencil holding clamp movable toward and away from said cutter, a latching device for supporting said clamp in raised position, and a pencil gage mounted upon said latching device for limiting the entrance of the pencil in said clamp.

16. In a pencil sharpening machine, the combination of a sharpening cutter and means for operating it, with a gravity operated pencil holding clamp movable toward and away from said cutter, a spring actuated latching device for supporting said clamp in raised position, and a pencil gaging plate

carried by said latching device and projected thereby in the path of a pencil for limiting the entrance of the pencil in said clamp when the latching device is in action.

17. In a pencil sharpening machine, the combination of a casing, a cutter mounted in said casing, guides formed upon said casing, a pencil holding clamp formed with depending guide rods operating in said casing guides, and a clamp supporting latching device mounted upon said casing and adapted to engage said rods.

18. In a pencil sharpening machine, the combination of a frame, a sharpening cutter mounted in said frame, a pencil holding clamp formed with depending guide rods having sliding bearings in said frame, one of said rods being formed with a latching notch or recess, and an automatic latching device mounted upon said frame and adapted to engage the notch or recess of said rod.

19. In a pencil sharpening machine, the combination of a frame, a sharpening cutter mounted in said frame, a pencil holding clamp formed with guide rods having sliding bearings in said frame, said clamp being movable toward and away from said cutter, and an automatic latching lever pivotally mounted upon said frame in position to engage one of said guide rods.

20. In a pencil sharpening machine, the combination of a frame, a sharpening cutter mounted in said frame, a pencil holding clamp movable toward and away from said cutter, notched guide rods depending from said clamp and having sliding bearings in said frame, and a pair of automatically operated latching levers pivotally mounted upon said frame and adapted to engage said guide rods for supporting the clamp in raised position.

21. In a pencil sharpening machine, the combination of a frame, a sharpening cutter mounted in said frame, a pencil holding clamp, guide rods depending from said clamp and having bearings in said frame, a latching lever pivotally mounted upon said frame and adapted to engage one of said rods, and a pencil gaging plate secured to said latching lever in position to project across the path of the pencil.

22. In a pencil sharpening machine, the combination of a frame, a rotary cutter-carrying member journaled in said frame, a pencil holding clamp movable toward and away from said cutter, a latching device for holding said clamp in raised position, and means carried by said rotary member for releasing said latching device.

23. In a pencil sharpening machine, the combination of a suitable frame, a rotary cutter-carrying frame journaled therein, a pencil holding clamp movable toward and away from said cutter, a latching lever

adapted to engage said clamp for holding it in raised position, a projection upon said lever, and a pin carried by said rotary frame adapted to engage said projection for releasing said latching device.

24. In a pencil sharpening machine, the combination with a suitable frame, a rotary member centrally journaled in said frame, a driving shaft geared to said rotary member, a pencil guiding recess formed in said rotary member, a rotary sharpening cutter journaled upon said rotary member at one side of said recess, a gear upon said cutter, a ring gear mounted upon said frame and meshing with the gear upon said cutter, gravity fed clamping means for engaging a pencil, and means independent of the pencil for supporting said clamping means in operative position.

25. In a pencil sharpening machine, the combination of a suitable casing, a rotary member journaled in upright position in said casing and formed with a pencil guiding recess, an upright sharpening cutter journaled in said rotary member at one side of said guiding recess, gearing for driving said rotary member and cutter, a pencil holding clamp movable vertically toward said rotary member and cutter, and means for supporting said clamp independently of said pencil.

26. In a pencil sharpening machine, the combination of a suitable casing, a top plate removably mounted upon said casing, a guide frame depending from said top plate and supported thereby within said casing, a rotary member within said depending

frame, a sharpening cutter carried by said rotary member, gearing for operating said rotary member and cutter, and a pencil holding clamp for presenting a pencil in operative relation to said cutter and provided with supporting means guided by said frame.

27. In a pencil sharpening machine, the combination of a suitable casing, a top plate mounted upon said casing, and formed with a central opening through it, a frame mounted upon said top plate and supported thereby within said casing, a rotary member journaled at its lower end upon said frame and at its upper end upon said top plate, said rotary member being formed with a contracted pencil guiding recess open upon one side and in axial alinement with the axis of rotation of said member, a sharpening cutter journaled in said rotary member and presented at the open side of said recess, an internal ring gear surrounding said rotary member and suitably supported from said top plate, a gear upon said sharpening cutter meshing with said internal ring gear, means for driving said rotary member, and a pencil supporting and feeding clamp arranged to present a pencil in said contracted recess in operative relation to said cutter and to automatically feed it thereto.

Signed at New York, N. Y., this 11th day of August, 1911.

LOUIS MYERS.
